DEFROSTER FOR REFRIGERATORS AND FREEZERS

Donald E. Holt, Plano, Ill., assignor to Zean W. Davis and Dorothy E. Davis, doing business as Davis Manufacturing Company, Plano, Ill., a general partnership of Illinois

Filed Nov. 1, 1963, Ser. No. 77,248

Term of patent 14 years

(Cl. D67—2)

Fig. 1

Fig. 2

Fig. 3

Fig. 4

Fig. 5

FIG. 1 is a top plan view of a defroster for refrigerators and freezers, embodying the design;

FIG. 2 is a side elevational view;

FIG. 3 is a bottom plan view;

FIG. 4 is an end elevational view, as viewed from the left end of FIG. 2, and

FIG. 5 is an end elevational view thereof, as viewed from the right end of FIG. 2.

The conventional electrical cord fragmentarily shown in FIGS. 2, 3 and 5 is broken away for convenience of illustration.

I claim:

The ornamental design for a defroster for refrigerators and freezers, substantially as shown and described.
